Kans.

Application March 15, 1939, Serial No. 262,000

1 Claim. (Cl. 267—9)

My invention relates to railway car trucks and more particularly to a truck provided with novel means of resiliently supporting the load to be carried thereby.

5 This invention is an improvement over that shown in my Patent 2,110,004, bearing date March 1, 1938.

In the railway car trucks of the known art, the bolsters are mounted upon a nest of springs, 10 usually a group of four at each spring plank, or alternatively upon elliptical springs. These springs are compressed under load and shock and recoil with approximately a force equal and opposite to that which caused them to be compressed. This recoil results in periodic oscillations and vibrations which depend upon the speed, the load, the wheel and track conditions. These oscillations will pass through many cycles before the car returns to its normal riding plane. 15 Excessive shocks due to spring recoil are transmitted to the car body and have been known to cause damage to the load, to the cars and to the track. Then, too, the oscillations resulting from excessive spring recoil cause rocking and 20 bouncing which tend to permit the wheels to leave the rails, thus presenting a danger of derailment. The difficulties above mentioned are not eliminated by increasing the spring capacity. Numerous attempts have been made to counter- 25 act this known condition by the use of snubbers, shock absorbers and damping springs which are intended to break up the undesirable harmonic motions.

In my Patent 2,110,004, I have shown one 30 spring construction in which periodic oscillations and vibrations are damped. In my previous construction, the cam members are formed along surfaces lying in a single plane. I have found that there is a tendency for the cams to move laterally with respect to the followers.

40 One object of this invention is to provide a construction in which lateral motion of the cams with respect to the followers is obviated.

In the accompanying drawing which forms 45 part of the instant specification and is to be read in conjunction therewith, and in which like reference numerals are used to indicate like parts in the various views;

Figure 1 is a fragmentary elevation with parts 50 in section, of a railway cam truck equipped with one embodiment of my invention.

Figure 2 is an end elevation of the spring, cam and follower assembly with a portion of the upper follower broken away.

55 Figure 3 is a side elevation of the spring, cam

and follower assembly shown in Figure 2, with parts in section.

Figure 4 is a sectional view, taken along the line 4—4 of Figure 3.

Figure 5 is a plan view of one of the follower members, showing the surfaces with which the cams coact.

In general, my invention contemplates the use of a pair of cams forced outwardly by springs whose axes are at right angles to the thrust 10 whereby friction to movement of the cam surfaces will act as a damping force, in which the cams are formed with surfaces lying along planes forming angles with each other.

More particularly, referring now to the drawing, 15 the wheels 1 support the customary axles 2, upon which are mounted spring planks 3. The spring planks carry a channel member 24 and support the spring assemblies of my invention. The spring assemblies support the usual truck 20 bolster 4, which, in turn, supports the railway car body.

The spring assembly comprises a lower follower member 5 and a like upper member 6.

Referring now to Figure 5, it will be seen that 25 the follower member is provided with a surface 7, inclined with respect to the horizontal and also inclined with respect to surface 7' which is likewise inclined to the horizontal. The surfaces 7 and 7' meet along the line 7a and form 30 a V. Similarly inclined surface 8 extends along a plane which forms an angle with the plane of inclined surface 8'. The cam members 11 and 14 are formed with correspondingly inclined surfaces adapted to coact with the inclined surfaces 35 of the followers 5 and 6. The surface 12 of the follower 14 is inclined with respect to the vertical and is formed along a plane which makes an angle with the plane of the surface 12a which is likewise inclined with respect to the vertical. 40 Similarly, the lower cam surface 13 is inclined to the vertical and is formed along a plane forming an angle with the plane of the inclined surface 13a. Cam member 11 is likewise formed with four sets of inclined surfaces. A pair of springs 18 and 22 urge the cam members 14 and 11 outwardly and into engagement with the respective inclined surfaces of the followers 5 and 6. A bolt 19 passes axially through the springs 45 18 and 22 and is provided with a bolt head 20 and a nut 21. The bolt head and the nut act as stops to limit the outward movement of the cam members 11 and 14.

In operation, the assembly is such that the lower members 5 are supported on the spring 55

planks as can readily be seen by reference to Figure 1. The upper followers 6 directly support the truck bolster 4. Since the load is carried by the bolsters, any thrust occasioned by the load 5 will be directly transmitted to the upper follower members 6. This thrust will serve to compress members 5 and 6, tending to move along toward each other. When this occurs, the inclined surfaces of the followers will force the cams 11 and 10 14 toward each other against the action of the springs 18 and 22. There will be motion of the follower members along the inclined surfaces of the cams. This motion is resisted by friction, which friction acts as a snubbing or damping 15 means, preventing harmonic motions. Due to the fact that the followers are formed with a pair of surfaces extending along intersecting planes, lateral motion of the cams with respect to the followers is prevented.

20 It will be seen that I have accomplished the objects of my invention and have provided a novel railway car truck fitted with a spring assembly comprising an improvement over my prior Patent 2,110,004. The coacting inclined surfaces

formed along intersecting planes act to prevent lateral motion of the cams.

Having thus described my invention, I claim:

In a railway truck, a spring assembly comprising in combination, a channel member having a pair of upstanding flanges formed with downwardly and inwardly inclined surfaces, said surfaces being formed along intersecting planes, a second channel member spaced above said first channel member having flanges formed with upwardly and inwardly inclined surfaces, a pair of cam members positioned between said channel members, having inclined surfaces in contact with the inclined surfaces of said channel members, a coil spring horizontally positioned between said cam members, urging them to cam said channel members apart, and a limiting rod axially positioned within the spring for limiting the outward movement of said cam members, recesses in the outside surfaces of the cam members adapted to 15 recess the end of the limiting rod below the surfaces of the cam members.

EDWARD P. O'CONNOR.
